SEWING MACHINES

Karl Winz, Kaiserslautern, Pfalz, Germany, assignor to G. M. Pfaff A.-G., Kaiserslautern, Pfalz, Germany, a joint-stock company

Application July 30, 1956, Serial No. 600,748

Claims priority, application Germany August 9, 1955

2 Claims. (Cl. 112—125)

This invention relates to sewing machines having a cutting arrangement for trimming or separating the stitched materials alongside the row of stitching.

It is one object of the present invention to provide a means whereby the engagement and disengagement of the cutting means may be effected whilst stitching is in progress and without the operator having to use the hands for such purpose.

This is in contrast to known arrangements where, for example, two manipulations of a control member are required to be made by an operator one for engagement of the cutter and the other for disengagement of the cutter. In one known machine this was done by applying pressure to a pressure plate secured to the cutter bar, the latter being disengaged by extracting a coupling pin from a recess in the cutter bar which is then returned to its initial position under the influence of a return spring. In another known machine the cutter bar is engaged and disengaged by the shifting of a lever on the arm of the machine. The same disadvantage is shared by cutting mechanisms in which the cutter must be swung out into a given non-operative position to be disengaged.

In accordance with the present invention the object is achieved by using a single control lever both for engagement and disengagement of the cutter, and acting always in the same direction, said control lever acting in the one case on the cutter bar to move it into operative position and at the same time to hold a pivoted disengagement lever inoperative, and acting in the other case on said pivoted lever to effect a release of the cutter bar.

A machine of the type in which the improved mechanism in accordance with the present invention can be incorporated to advantage is disclosed in U. S. Patent No. 2,538,271 to G. M. Reimer et al.

Further features of the invention and details of the advantages obtained thereby are apparent from the following description of one embodiment, illustrated in the accompanying drawings, wherein:

Fig. 1 is a perspective view of a sewing machine taken from the rear, such machine having the invention incorporated in it. The cover plate for the head is removed;

Fig. 2 is a front perspective view of a part of the machine, with the cutter bar disengaged;

Fig. 3 is a view similar to Fig. 2, but with the cutter bar engaged and with the arm in the engaged position;

Fig. 4 shows the arm in the resting position; and

Fig. 5 shows the arm in the position at the beginning of disengagement.

The sewing machine consisting of base plate 3, support 4, arm 5 and head 6 is mounted in cutout portion 1 of table top 2. The reciprocating needle bar 8 is arranged in the head 6 which carries the needle 7 and is driven in the usual manner by way of a crank operated by the arm shaft which is not shown in the drawing. The presser bar 10 carrying the presser foot 9 may be raised as desired either by the lifting lever 11 acted upon by a knee lever or treadle, or by the finger lever 12.

2

Slidably arranged in the head 6 is the cutter bar 13 which carries at its lower end the cutter blade 14. The latter co-operates in known manner with a stationary lower cutter blade (not shown) mounted in the stitch plate. When the cutter is in operation, it reciprocates vertically to effect a trimming or severing operation on the fabric alongside the line of stitching. This is well known in the art. The return spring 16, which is connected at one end to the hook 17 of the cutter bar 13 and at the other end to the hook 18 fixed in the head 6, draws the cutter bar 13 upwards into the position shown in Figs. 1 and 2 when the cutter drive is disconnected.

The cutter drive is effected in known manner from an eccentric (not shown) arranged on the arm shaft, an eccentric rod 19 and a drive lever 20 which is adjustably linked thereto. This lever 20 is secured to the cutter drive shaft 22 mounted in lugs 21 of the head 6, such shaft having clamped to it the cutter drive crank 23. To the cutter drive crank 23 is secured the sleeve or bushing 24 which receives a slideable pin 25 the inner end of which may engage the notch or recess 26 in the edge of the cutter bar 13. The pin 25, the outer end of which is provided with the nut 27 is under the influence of a spring—not shown—which presses it continuously against the front edge 28 of the cutter bar 13, and therefore tends to place it in the notch or recess 26.

The sleeve 24 with the pin 25 projects freely through a slot 29 in the head plate 30 (Fig. 2) which is secured to the head of the machine by means of screws 31. As the said arm shaft rotates, the crank 23 oscillates and therefore moves the pin 25 up and down in a short, substantially vertical path.

In the disengaged position of the cutter 14 (Figs. 1 and 2) the inner end of pin 25 merely slides up and down on to the edge 28 of the lower part of the cutter bar 13, below the notch or recess 26. If, for engaging the cutter 14, the cutter bar 13 is pressed downwardly against the action of the spring 16 until the pin 25 slides into the recess 26 in the cutter bar 13 oscillating movements of the driving crank 23 are then transmitted to the cutter bar 13 as vertical reciprocations. The extent of the movement of the cutter bar 13 can be fixed by adjusting the eccentric rod 19 on the driving lever 20.

Disengagement of the cutter 14 is effected by extracting the pin 25 from the recess 26 of the cutter bar 13, by means of the nut 27, whereby the cutter bar 13 returns to its initial raised position under the action of the return spring 16 (Figs. 1 and 2).

According to this invention, instead of the usual pressure plate for the cutter bar, there is arranged at the upper end of the cutter bar 13, a pressure member 32 (Fig. 2) which is secured to the cutter bar 13 by a screw 33. In a bore 34 of the pressure member 32 is displaceably mounted a slideable bolt 35 having a flange 36 at its one end against which one end a spring 37 reacts, this spring being wound around the bolt 35. The other end of such spring is biased against the adjacent end of the pressure member 32.

A pin 38 extending upwardly from the bolt 35 is guided in a slot 39 in the top of the pressure member 32. The spring 37 presses the bolt 35 to the right (Figs. 2-5) until such pin 38 strikes against the closed end of the slot 39 at that end of member 32.

A carrier or bracket 40, having two arms 41 between which a trip lever 42 is mounted on screw 43, is secured to the head plate 30 (Figs. 1 and 4) by means of the screws 31 which hold the head plate in position. The trip lever 42 has a downwardly extending bifurcated arm 44 which embraces the sleeve 24 and has an upwardly extending arm 45, shaped at the top to provide a stop member 46. The trip lever 42 is under the influence of

a U-shaped spring 47 which is provided with coils in both arms. This spring is suspended from a slot 48 in the arm 45 so that its arms hang down one on each side of that arm and their lower extremities enter into blind holes 48a in the arms 41 of the said carrier 40.

The spring 47 tends to keep the trip lever 42 in position of rest shown in Fig. 4, namely with the forked end 44 disposed in the immediate vicinity of the nut 27 of the pin 25, but without actuating the latter. During the up and down movement of the cutter bar 13, the sleeve 24 does not leave the fork 44.

On the rear end of the arm 5 of the sewing machine there is mounted on a bolt 49, jointly with the lifting lever 11, a double-armed control lever 50 (Fig. 1) the rear arm 51 of which is pivotally connected to a pressure rod 52 constrained by a pressure spring 53. The pressure rod 52 passes through a bore 54 in the base plate 3 of the machine, and under the table top 2 where, through a reversing lever 55, it is connected to an actuating rod 56 which is moved in turn by a control member such as a knee lever, pedal, magnet or the like (not shown). The front arm 57 of the control lever 50 is bent so that its end portion 58, extending horizontally parallel to the upper edge of the head plate 30, is disposed just above the pressure member 32 when the cutter bar is disengaged. An angle member 60, the free end of which is approximately parallel with the said portion 58, is secured to such portion by means of screws 59.

In Figs. 1 and 2 the cutter bar 13 is raised, being in the disengaged position. The pressure bolt 35 extends out of the pressure member 32 at its head end under the pressure of the spring 37 and the pin 38 is disposed against the closed end of the slot 39. The upper arm 45 of the trip lever 42 is disposed at the front of the bolt 35 under the action of the spring 47 and the forward end 58 of the control lever 50 is on the right side of the pin 38 (Fig. 2) in the raised position.

To engage the cutter the control member is actuated to pull down the rod 56, thereby moving the control lever 50 clockwise (Fig. 1) and therefore counterclockwise in Figs. 2-5. At the same time the cutter bar 13 is moved downwardly by the overhanging portion 58, against the action of the spring 47, and simultaneously, because of the circular movement of part 58 about the pivot bolt 49, the pin 38 is moved to the left (Fig. 2) together with the bolt 35. This bolt 35, abutting the edge 46 of arm 45 of the trip lever 42, moves such lever counterclockwise against the action of the spring 47, until the descending angle member 60 on the said portion 58 of the control lever 50, instead of striking against the edge 46 of the arm 45 passes said arm 45 (Fig. 3). When eventually the arm 45 of the trip lever 42 slides from the front of the descending pressure bolt 35 it is urged by spring 47 on to the outer face of angle member 60 and is now retained thereby. The cutter bar 13 having been pressed down by the end 58 sufficiently for the pin 25 on the cutter drive crank 23 to engage the recess or notch 26 of the cutter bar 13, the cutter bar is now taken up by the drive and reciprocates vertically, the pin 25 being retained in the notch 26 by the aforesaid spring (not shown).

Fig. 3 shows this position, in which the cutter bar 13 is engaged and the front end 58 of the control lever 50 has arrived at the end of its swinging movement. When the control member is released, the control lever 50 with its end 58 and the angle member 60 and the trip lever 42 return to their initial position (Fig. 4).

If the cutter 14 is to be disengaged, the control member is actuated again to pull down rod 56 and, in the same manner as before, owing to the ensuing swinging of the control lever 50 counterclockwise (Fig. 5), the angle member 60 now strikes against the stop member 46 of the arm 45, since the latter can no longer be kept out of the path of movement of the angle member 60 by the pressure bolt 35. As a result, the trip lever 42

is swung clockwise (Fig. 5). At the same time the forked end 44 of the trip lever 42 engages the nut 27 and pulls the pin 25 out of recess 26 in the cutter bar 13 (Fig. 5) which then, as described above, returns to its initial position under the influence of spring 16. Upon the release of the control member, the front end 58 of the control lever 50 and the trip lever 42 return to the position shown in Fig. 2.

The device has been explained with reference to the example of an edge cutter or trimmer. It may also be used for the engagement and disengagement of cutters for severing material into separate pieces.

What I claim is:

1. In a sewing machine having a work support and a machine arm including a main drive shaft and supporting a machine head vertically above said work support, a reciprocating cutter bar mounted in said machine head having a cutter end extending downwardly and an operating end extending upwardly from said machine head and having a recess, a spring extending between said cutter bar and said machine head biasing said cutter bar toward inoperative position away from said work support, driving means including a crank arm and a shaft journaled in the machine arm linking said cutter bar by way of a slideable pin on said crank arm for reciprocating movement to said main drive shaft, said slideable pin extending through an aperture in the machine head for engaging said recess, an adjusting nut disposed endwise and circumferentially of said slideable pin, a pressure member disposed on the operating end of said cutter bar and having a slot, a spring biased slideable bolt extending through said pressure member and having an outwardly extending conformation movable in said slot, a trip lever extending substantially parallel to said cutter bar and mounted on the machine head having one arm in operating engagement with said adjusting nut and the other arm proximate said pressure bolt, a spring secured to one arm of said lever and biasing said lever toward said pressure bolt, a double armed control lever mounted on a pivot laterally of the machine including manipulating means and spring biased toward inoperative position, said control lever extending lengthwise of the machine arm and having an upwardly extending portion presenting a transverse member proximate said pressure member transversely of said slideable bolt arcuately movable about said pivot into engagement with said pressure member and said conformation to move said other arm outwardly, said one arm inwardly, and said cutter bar downwardly thereby permitting said slideable pin to enter said recess and cause said cutter bar to follow the movement of said crank arm.

2. In a sewing machine having a work support and a machine arm including a main drive shaft and supporting a machine head vertically above said work support, a reciprocating cutter bar mounted in said machine head having a cutter end extending downwardly and an operating end extending upwardly from said machine head and having a recess, a spring extending between said cutter bar and said machine head biasing said cutter bar toward inoperative position away from said work support, driving means including a crank arm and a shaft journaled in the machine arm linking said cutter bar by way of a slideable pin on said crank arm for reciprocating movement to said main drive shaft, said slideable pin extending through an aperture in the machine head for engaging said recess, an adjusting nut disposed endwise and circumferentially of said slideable pin, a pressure member disposed on the operating end of said cutter bar and having a slot, a spring biased slideable bolt extending through said pressure member and having an outwardly extending conformation movable in said slot, a trip lever extending substantially parallel to said cutter bar and mounted on the machine head having one arm in operating engagement with said adjusting nut and the other arm proximate said pressure bolt, a spring secured to one arm of said lever and biasing said lever toward said pressure bolt, a double armed control lever mounted on a pivot laterally of the machine including manipulating means and spring biased toward inoperative position, said control lever extending lengthwise of the machine arm and having an upwardly extending portion presenting a transverse member proximate said pressure member transversely of said slideable bolt arcuately movable about said pivot into engagement with said pressure member and said conformation to move said other arm outwardly, said one arm inwardly, and said cutter bar downwardly thereby permitting said slideable pin to enter said recess and cause said cutter bar to follow the movement of said crank arm.

arm of said lever and biasing said lever toward said pressure bolt, a double armed control lever mounted on a pivot laterally of the machine including manipulating means and spring biased toward inoperative position, said control lever extending lengthwise of the machine arm and having an upwardly extending portion presenting a transverse member proximate said pressure member transversely of said slidable bolt arcuately movable about said pivot into engagement with said pressure member and said conformation to move said other arm outwardly, said one arm inwardly, and said cutter bar downwardly when said cutter bar is idle, and an angular abutment member on said transverse member adapted when said

cutter bar is in operative position to engage said one arm while said slidable pin engages said recess and cause pivotal movement of said trip lever to withdraw said nut and thereby said pin from said recess and release 5 said cutter bar for movement by said biasing spring.
